UNITED STATES PATENT OFFICE

MARY D. NEILSON, OF MINNEAPOLIS, MINNESOTA

BLOOMERS FOR WOMEN

Application filed July 14, 1930. Serial No. 467,816.

My invention relates to bloomers for women and has for its object to provide a bloomer garment that is peculiarly sanitary and comfortable and which is provided with a completely closing side opening. In general the bloomer garment is of the type shown in my Patent No. 1,487,971, issued March 25, 1924, wherein, owing to the manner of fabricating the garment excess fullness is thrown through from the crotch back and to the seat of the garment. Such bloomer garments have been made to slip off at the waist and to open directly back at the center and to open along the side. Where the garment is made in the form of a slip it cannot be slipped off and some form of opening must be provided. There has been objection to an opening at the side for the reason that in order to effect complete closure a number of fastenings along the side have been necessary, and even then there is a tendency to gap and the garment does not hang and lie straight and smooth over the hips.

My invention has for its object to add material to the back of the garment along one side and to provide fastenings at the bottom only, thus effecting a closure that remains in position, that will not gap or bulge, that is comfortable when it is closed and that is particularly simple and easy to unfasten and open.

The full objects and advantages of my invention will appear in connection with the detailed description thereof, and its novel features are particularly pointed out in the claim.

In the drawing illustrating the application of my invention,—

Fig. 1 shows a manikin figure with the garment attached and the side opening unfastened. Fig. 2 is a similar manikin figure with the garment in position and fastened. Fig. 3 is a pattern view of the back of the bloomer portion of the garment. Fig. 4 is a pattern view of the two front pieces of the bloomer portion of the garment. Fig. 5 is a pattern view of the insert piece applied to the garment.

In practice, as fully described in my patent referred to, the back 10 has its edges 11 and

12 sewed to the edges 13 and 14 of front sections 15 and 16. The edges 11 and 12 may be longer than the edges 13 and 14, for which reason the edges 11 and 12 must be, and in practice are, pleated in, being attached to the edges 13 and 14. The edges 17 and 18 of the front pieces 15 and 16 are sewed together, and also the curved portions 19 and 20 of said front pieces 15 and 16 are sewed together. The straight portions 21 and 22 of the front pieces 15 and 16 are sewed to the curved bottom line 23 of the back member 10. This will produce a full-seat garment of the type described in my said patent.

In the practice of my invention, an outer edge of one of the front pieces, as the edge 14 of front piece 16, is not sewed or fastened to the corresponding edge of the back piece 10, as the edge 12 thereof, but I provide a special triangular piece 23 having similar edges 24 and 25 each of the same length as the edges 13 and 14 of the front pieces 15 and 16. The edge 25 of the piece 23 is sewed to the edge 12 of the back piece 10, as indicated at 26 in Figs. 1 and 2, with take-up of the extra length of the edge 12 through pleating, and thus the production of requisite fullness, if that is desired. That leaves an edge 24 of the attached piece 23 of the same length as the edge 14 of the front piece 16. The front piece 16, however, will normally overlap the whole of the piece 23 so that its edge 14 will normally coincide with the seam 26. This because the front pieces 15 and 16 are cut so as to reach that point and normally have their edges sewed to the edges of the back piece 10.

At the hem forming the lower part of the garment, I provide a pair of snaps 27 of well-known construction. When the garment is in normal wearing position, as in Fig. 2, the snaps will be closed and the front 16 will overlie the piece 23, as clearly shown in Fig. 4. When it is desired to open the garment it is only necessary to pull open the snaps 27 and the side opening is effectively and completely provided. It is particularly effective because it extends fully up to the waist band 29. The construction can be employed for bloomers only, in which case the

garment would end at the waistband 29. It is, however, a particularly desirable construction to be employed with a brassière waist 30, as shown, which will normally be closed along the side by buttons or snaps 31.

I claim:

A bloomer garment comprising a back piece and front pieces adapted to be sewed to the edges of the back piece and to each other, 10 the edges of the said back piece being longer than the edges of the front piece whereby the back piece edges are gathered where sewed to the front piece edges, an insert of roughly triangular shape having its two long edges 15 equal in length to each other and to the edge of the front piece and having one of its edges sewed to an edge of the back piece said back piece edge being gathered thereto, and a pair of fasteners spaced apart along a circumferential line at the bottom of the front piece 20 and of the insert for holding said front piece in overlapping position in respect to said insert.

In testimony whereof I hereunto affix my
25 signature.

MARY D. NEILSON.
